UNITED STATES PATENT OFFICE.

HENRY A. KESSLER, OF LOS ANGELES, CALIFORNIA.

FLY-CATCHER.

No. 878,207.

Specification of Letters Patent.

Patented Feb. 4, 1908.

Application filed April 19, 1907. Serial No. 369,172.

To all whom it may concern:

Be it known that I, HENRY A. KESSLER, citizen of the United States, residing at Los Angeles, in the county of Los Angeles and 5 State of California, have invented certain new and useful Improvements in Fly-Catchers, of which the following is a specification.

This invention has for its object a simple, 10 cheap, durable and efficient construction of fly catcher, and the invention consists in certain constructions and arrangements of the parts which I shall hereinafter fully describe and point out the novel features in the 15 appended claims.

For a full understanding of the invention and the merits thereof and also to acquire a knowledge of the details of construction of the means for effecting the result, reference 20 is to be had to the following description and accompanying drawings, in which:

Figure 1 is a perspective view of my improved fly catcher; Fig. 2 is a sectional side elevation thereof; and, Fig. 3 is a detail perspective view of the upper portion of the 25 paste applying device with the scraper attachment supported thereon.

Corresponding and like parts are referred to in the following description and indicated 30 in all the views of the drawings by the same reference characters.

My improved fly catcher comprises a base 1 from which a post or rod 2 extends and a bell shaped paste applying reservoir adapted 35 to rest on the base and mounted to slide up and down on the rod. The applying device 3 embodies a paste reservoir 4, the bottom wall 6 of which is preferably sloping, and the said bottom is formed with an opening 40 snugly receiving the rod as clearly illustrated in the drawings. The paste reservoir is normally closed by a screw cap 5 or similar closure which may be removed in order to fill the reservoir with paste. The 45 cap 5 supports a tube 8 which encircles the rod, and to the upper end 9 of said tube and on a lateral extension 10 thereof, two semi-circular plates 11 are pivoted so as to swing towards and from the rod, said plates being 50 provided with curved recesses 12 adapted to encircle the rod when the two plates are

closed. The free ends of the plates 11 are provided, respectively, with a latch and a keeper so that they may be held in close relation around the rod. If desired, the 55 hinge or pintle of the two plates may be of the spring variety so as to swing the plates away from each other when they are unlatched.

In the practical use of my device, the paste 60 applying device normally rests upon the base 1 with the rod 2 covered with paste that has been applied thereto by a previous downward movement of the applying device on the rod. The flies will be attracted by the 65 paste on the rod and be entangled therein, and whenever desired the paste applying device 3 may be then moved upwardly on the rod, the plates 11 being closed together during this movement and serving to effectually 70 scrape the dead flies from the rod. The scraper plates 11 are then swung outwardly and the paste applying device 3 slid downwardly again on the rod which will effect a distribution of paste over the latter. 75

If desired, the bottom of the reservoir may be provided with a rubber washer 7 snugly encircling the rod so as to keep the same free from paste.

From the foregoing description in connection with the accompanying drawing, it will be seen that I have provided a very simple device of this character which may be easily operated and which may be made more or less ornamental, as desired, so as to avoid 85 the unsightly appearance that so many devices for this purpose display.

Having thus described the invention, what is claimed as new is:

1. A fly catcher comprising a base, a rod 90 supported thereon, a paste applying device mounted to slide on said rod and adapted to apply paste thereto, and a scraper mounted to slide on said rod above the paste applying device and consisting of pivoted plates spring 95 pressed to swing outwardly away from the rod, said plates being provided with a latch and a keeper, respectively, designed for interlocking engagement to hold the plates clamped around the rod. 100

2. A fly catcher, comprising a base, a rod supported thereon, a paste applying reservoir

mounted to slide on said rod and provided with a closure, said cap being provided with a tube encircling the rod and provided with a lateral extension 10, and plates adapted to encircle said rod and pivotally mounted on the said extension, as and for the purpose set forth.

In testimony whereof I affix my signature in presence of two witnesses.

HENRY A. KESSLER. [L. S.]
